UNITED STATES PATENT OFFICE.

FREDERICK BENZINGER, OF UNION HILL, NEW JERSEY, AND LOUIS FREUND, OF NEW YORK, N. Y.

SKEIN-HOLDING DEVICE.

SPECIFICATION forming part of Letters Patent No. 740,616, dated October 6, 1903.

Application filed October 23, 1902. Serial No. 128,501. (No model.)

To all whom it may concern:

Be it known that we, FREDERICK BENZINGER, residing at Union Hill, in the county of Hudson and State of New Jersey, and LOUIS 5 FREUND, residing at New York, in the county of New York and State of New York, citizens of the United States, have invented certain new and useful Improvements in Skein-Holding Devices, of which the following is a specification.

This invention relates to a device for holding one or more skeins of thread so that single threads may be readily withdrawn from a group without disturbing the remainder of 10 the threads in the same group.

The invention consists of a suitable support with a gripping device of peculiar construction, described more fully hereinafter, which allows of the withdrawal of one of a group of 15 threads and at the same time clamps and holds the remainder of the group in place.

Referring to the drawings, Figure 1 is a side elevation of a skein-holding device, illustrating our invention. Fig. 2 is an enlarged 20 end elevation of a plurality of gripping devices mounted on a common support. Figs. 3 and 4 are details illustrating a modification of the gripping device. Fig. 5 is an end view of a skein-holding device such as shown in 25 Fig. 1 with the gripping device which is shown in Figs. 2 and 6 removed to better illustrate a grooved construction of the platform-support. Fig. 6 is a sectional elevation of 30 the parts shown in Fig. 2.

The same parts in the different views are 35 represented by the same reference-figures.

The support for the skeins is preferably made of wood and in one or two parts joined together by a clamp 2 to form an inverted-V- 40 shaped member, (designated by 1.)

3 represents legs of any suitable design, preferably constructed of metal to give stability to the device. These legs 3 may be fastened to the support 1 by means of screws 4, the 45 feet being preferably provided with felt cushions 5, so that the device may be used on a polished table without marring the surface of same.

The gripping-device holder is usually of 50 metal and is made of channel or U shaped cross-section to give necessary stiffness. This

holder is designated by 6 and is slotted at 7 transversely to serve as a guide for a tension-device stem. This stem 8 is provided with a rubber grip 9, preferably of tubular form, to 55 allow of more flexibility in gripping and holding the group of threads 10. The stem, with rubber grip attached, is held in engagement with the group of threads by means of a spring 11, which acts against the inner side of the 60 holder 6 and the stem 8, the stem being provided with a shoulder and also with an extension passing through the spring and holder and acting as a guide for the upper end of the stem, as shown at 12.

The gripping device admits of other constructions than the one shown—as, for instance, the rubber grip may be held against and in engagement with the group of threads by means of a flat spring 11', connected directly from said grip to the holder, the object being to provide a flexible grip and means for holding said grip in engagement with the group of threads.

The holder 6, which carries one or more of the 75 independent gripping devices, as described, is preferably hinged at 13 to allow of its being raised to an inoperative or open position for removing or replacing the skeins of thread. The holder when closed may be held in its 80 operative position by means of a suitable spring-catch 14 in conjunction with a pin 15, which pin also serves as a handle to lift the holder.

In order to secure a more perfect contact 85 between the group of threads and the rubber grip, the support 1 is grooved on its upper surface. These grooves are shown at 16 and correspond in number and shape with the rubber grips. They are parallel one with the 90 other and may extend the entire length of the support. These grooves facilitate the location of the skeins and the separation of one skein from another. The drawings show only one skein or group of threads held by the device, while the construction, as shown, permits of any number up to twelve of separate skeins or groups of thread of different size or color being held independent one from another.

Two gripping devices are shown, one at 95 each end of the support, which permits of

the thread being withdrawn from either end of said support. When used from one side only, it is not necessary to provide a gripping device at both ends.

5 We do not wish to be understood as limiting ourselves to the details of construction shown and described, as it will be evident that many modifications might be made within the purview of our invention.

10 What we claim is—

1. In a skein-holding device, the combination with a platform-support, of a flexible gripping device carried by said support and coacting therewith to simultaneously grip a group of threads.

15 2. In a skein-holding device, the combination with a grooved platform-support, of a flexible gripping device carried by said support and coacting with the groove of said support to simultaneously grip a group of threads.

20 3. In a skein-holding device, the combination of a grooved skein-support having a plurality of parallel grooves and a plurality of independent gripping devices coacting with said grooves to simultaneously grip groups of thread.

25 4. In a skein-holding device, the combination of a platform-support and a flexible gripping device coacting with said support to grip a group of threads and shiftable to an inoperative position in relation thereto.

30 5. In a skein-holding device, the combination of a skein-support and a rubber gripping device carried by said support and coacting therewith to simultaneously and yieldingly grip a group of threads.

35 6. In a skein-holding device, the combination of a platform-support and a spring-pressed flexible gripping device carried by said support and coacting therewith to simultaneously grip a group of threads.

7. In a skein-holding device, the combination of a skein-support and a spring-pressed rubber gripping device carried by said support and coacting therewith to simultaneously grip a group of threads. 45

8. In a skein-holding device, the combination of a grooved skein-support and a rubber gripping device spring-pressed into engagement therewith, carried by said support and coacting therewith to simultaneously grip a group of threads. 50

9. In a skein-holding device, the combination of a grooved skein-support and a tubular rubber grip carried by said support and coacting therewith to simultaneously grip a group of threads. 55

10. In a skein-holding device, the combination with a platform skein-support, of a holder pivoted at one side of said support, and a gripping device carried by said holder and coacting with said support to simultaneously grip a group of threads. 60

11. In a skein-holding device, the combination of an inverted-V-shaped skein-support and a holder carried by said support and coacting therewith to simultaneously grip a group of threads. 65

12. In a skein-holding device, the combination of a skein-support and a longitudinally channelled and transversely-slotted holder guiding and carrying a gripping device and coacting with said support to simultaneously grip a group of threads. 70

Signed at New York, in the county of New York and State of New York, this 18th day of October, A. D. 1902.

FREDERICK BENZINGER.
LOUIS FREUND.
